SAFETY BOTTLE BREAKER

Theodore R. Heman and Ferdinand Gruenes,
Chicago, Ill.; said Gruenes assignor to said
Heman

Application May 11, 1936, Serial No. 79,208

1 Claim. (Cl. 83—93)

This invention relates to certain novel improvements in safety bottle breakers, and has for its principal object the provision of an improved construction of this character which will be highly efficient in use and economical in manufacture.

In the sale of certain bottled products, it is unlawful for the consumer or the merchant last handling the bottled product to refill the bottle for resale, and in many instances the law requires that the bottle be destroyed. Prior to our invention it was the universal practice to deposit the bottle in a container, such as a refuse can, and break the bottle by means of some implement suitable for that purpose or to deposit the bottles in a pile and then break or otherwise crush the same. Regardless of this method of destroying the bottle, it is obvious that the practice of such method not only is dangerous to the one breaking up the bottle or bottles, but is dangerous in the respect that the broken bottles become scattered over a substantial area, thus jeopardizing passersby or the like.

It is, therefore, one of the many objects of this invention to provide a bottle breaker which assures safety to the operator during the breaking operation and which prevents the broken bottle or the fragments thereof to become scattered or otherwise disposed of.

30 A further object of the invention is to provide within a closed container a bottle support and bottle breaker, the latter being operable by action of the cover of the container.

Other objects will appear hereinafter.

35 The invention consists in the novel combination and arrangement of parts to be hereinafter described and claimed.

The invention will be best understood by reference to the accompanying drawing showing the 40 preferred form of construction, and in which:

Fig. 1 is a perspective view of the invention;

Fig. 2 is a fragmentary sectional detail view of the same taken substantially on line 2—2 of Fig. 1;

45 Fig. 3 is a fragmentary sectional detail view similar to that shown in Fig. 2 by illustrating the cover in an open position; and

Fig. 4 is a horizontal sectional detail view of the same taken substantially on line 4—4 of Fig. 2.

Referring to the drawing illustrating the preferred form of construction of our invention, a container is indicated at 10, and this container includes side walls 11, a bottom 12, and a cover 13 hinged to one of the side walls, as at 14,

through the medium of suitable hinge elements 15.

To facilitate movement of the container about, we provide a handle 16 having its opposite end portions 17 pivotally secured, as at 18, to adjacent side walls of the container 10.

Formed as a part of the cover 12 are finger portions 19 which facilitate opening and closing of the cover 13. One of the side walls of the container is provided with a foot rest 20 of an angular formation whereby when the device is in operation, the operator may place his foot upon the rest 20 to prevent the container from moving about during the opening and closing action of the cover 13.

Arranged within the container and secured to one of the side walls 11, as at 21, is a bottle support 22 in the form of a narrow strip of material as best shown in Figs. 2 and 4. Spaced from this bottle support 22 and secured to one of the side walls 11 is a cooperating bottle support 23 of a shape and size adapted to receive that portion of the bottle adjacent the mouth thereof.

Pivoted secured within the container through the medium of a pintle rod 24 having connection 25 with opposite corresponding side walls of the container 10 is a bottle breaker 25 including a hammerhead 26 adapted to engage the bottle 50 a predetermined distance adjacent the support 22.

Engaging the lower edge portion 46 of the bottle breaker 25 is the bight 27 of a link 28 pivotally secured to an arm 29, as at 30. This arm 29 is pivoted, as at 31, to adjacent side wall 11 of the cabinet 10. The end 47 of the arm 29 is connected to a link 35 through the medium of a slot and pin connection 36. This link 35 in turn is pivotally connected, as at 37, to a lug 38 secured to the cover 13.

A latch structure is provided for releasably latching the breaker 25 in an inoperative position when the cover 13 is opened, and this latch structure is constructed and designed so as to operate automatically to release the breaker when the cover 12 is moved to closed position.

This latch structure includes a latch arm 39 pivoted to the adjacent side wall of the cabinet 10, as at 40, and is adapted to have latched engagement, as at 41, with an adjacent portion indicated at 42 of the breaker 25. This latch arm 39 is pivotally connected to an operating link 43 through the medium of a link 44. This operating link 43 is pivotally mounted as at 48 upon the side wall 11 and has an angled end portion 45 adapted to be engaged by the arm 29 whereby 55

to pivot the latch arm 39 upwardly to disengage the latch head 41 from the portion 42 of the breaker 25 when the cover is moved into closed position.

5 The operation of the latch mechanism is such that when the cover is raised hammer arm 46 is likewise raised and simultaneously therewith the latch arm 39 is moved upwardly when the angled head part 42 of the arm 46 engages the end portion 41 of the latch arm 39, and as soon as the hammer of arm 46 approaches its upward limit the latch 39 falls downwardly by gravity so that the angled latch portion 41 thereof is positioned in front of the angled end portion 42 of arm 46, and thus further downward movement of the hammer is prevented until such time as the latch 39 is again moved upwardly by the operation of the cover actuated levers 44-43 when the latch extremity 41 is slipped upwardly 10 past the extension 42 on the hammer arm 46.

15 20 The operation of the device is as follows: A bottle is disposed within the container with the body portion B of the bottle resting upon the support 22 and the neck portion N resting upon the support 23. Prior to the positioning of the bottle 27 upon the supports, the cover is raised into open position. In raising this cover 13 into open position, the arm 29 acting through the link 28 elevates the breaker 25 in the position shown in Fig. 3 with the spring 34 placed under substantial tension. The resting of this breaker 25 in the position shown will dispose the latch head 41 of the latch arm 39 in latched engagement with the portion 42 of the breaker 25, the operating link 43 being disposed with its angled end portion 45 in a position to be engaged by the arm 29. The bottle is then placed upon the supports in the manner hereinbefore stated.

25 30 35 To break the bottle, the operator closes the cover 13 to cause the arm 29 to engage the angled portion 45 of the operating link 43, whereupon the arm 39 is pivoted upwardly to disengage the latch head 41 from the portion 42, whereupon the breaker 25 under the action of the spring 34 is caused to come down in hammer-like force 40 45 upon the bottle 50 and break the bottle. A stop member 51 is provided upon the side wall 11 and is disposed in a position to take the force of the blow of the hammer before the head portion 26 strikes the bottle support 23. Upon 50 55 breaking of the bottle, the broken portions thereof will fall from their supports 22 and 23 into the bottom portion of the container 10. In this manner we provide a means for breaking bottles in a manner such as will assure safety to the operator.

The device breaking the bottles within a con-

tainer also provides a temporary place of confinement for the broken and fragmentary portions of the bottles.

It is to be noted that the hammer portion is about to be released when the cover is 98% closed, and that upon the tripping of the latch 43-44-39 the cover is 100% closed, thus assuring, upon the striking of the bottle by the hammer, that no fragments or splinters of glass can escape from the confines of the container 10. 10

15 While we have illustrated and described the preferred form of construction for carrying our invention into effect, this is capable of variation and modification without departing from the spirit of the invention. We, therefore, do not 15 wish to be limited to the precise details of construction set forth, but desire to avail ourselves of such variations and modifications as come within the scope of the appended claim.

20 Having thus described our invention, what we claim as new and desire to protect by Letters Patent is:

In a device of the class described including a receptacle and a hinged cover for said receptacle, hammer mechanism comprising a hammer arm 25 pivoted between its ends in said receptacle and having a hammer at one of said ends, and an actuating lever pivoted between its ends in said receptacle, spring means attaching one end of said actuating lever to the end of said hammer 30 35 arm opposite the hammer, a link pivotally attaching the free end of said actuating lever opposite said spring means to said cover, a setting lever having pivotal connection with said actuating lever at a point on the latter between the pivotal mounting thereof and the end to which said link is attached, said setting lever having sliding engagement with said hammer arm along an edge thereof between the pivotal mounting of the same and said hammer whereby to move the 40 45 hammer arm in a particular direction to set the same responsive to opening of the cover, and trip mechanism including a locking lever pivoted near one end opposite said hammer in set position and having an opposite free end disposed to move in blocking position relative to said hammer arm when the same is set as aforesaid to hold the same in set position, and tripping lever means operatively connected with said locking lever and having a portion positioned for engagement by 50 55 said actuating lever when the cover is closed whereby to release said hammer arm for breaking movement out of set position by said spring means.
